UNITED STATES PATENT OFFICE

134,251

DESIGN FOR A SERVICE FLAG

Alexander Morrison, Williamson, N. Y.

Application July 27, 1942, Serial No. 107,728

Term of patent 7 years

To all whom it may concern:

Be it known that I, Alexander Morrison, a citizen of the United States, residing at Williamson, in the county of Wayne and State of New York, have invented a new, original, and ornamental Design for a Service Flag, of which the following is a specification, reference being had to the accompanying drawing, forming part thereof.

In the drawing:

I claim:

The ornamental design for a service flag, substantially as shown.

ALEXANDER MORRISON.
